UNITED STATES PATENT OFFICE.

CYRUS T. SCHIRMER, OF NEWTON, MASSACHUSETTS, ASSIGNOR TO THE HOLTZER-CABOT ELECTRIC COMPANY, OF ROXBURY, MASSACHUSETTS, A CORPORATION OF MASSACHUSETTS.

ELAPSED-TIME RECORDER.

Application filed April 22, 1922. Serial No. 556,005.

To all whom it may concern:

Be it known that I, CYRUS T. SCHIRMER, a citizen of the United States, residing at Newton, in the county of Middlesex and 5 State of Massachusetts, have invented certain new and useful Improvements in Elapsed-Time Recorders; and I do hereby declare the following to be a full, clear, and exact description of the invention, such as 10 will enable others skilled in the art to which it appertains to make and use the same.

The present invention relates to an improvement in elapsed time recorders.

The object of the invention is to produce 15 an apparatus by which the time which elapses between the giving of a signal and the performance of another act by the person receiving the signal may be recorded. For example, a hospital might be equipped 20 with such an apparatus, operating so that upon the pushing of a button by a patient, a buzzer would be sounded at the nurses' desk and a pilot lamp lit there at the same time. Upon the release of the pressure 25 upon the push button by the patient, the buzzer would cease sounding, but the pilot lamp would remain lit, as also a lamp over or at the patient's room or bed. Then the time when the patient pushed the button 30 would be recorded on a strip of paper, and the length of time which elapsed before the nurse reached the patient to answer the call would be indicated. The nurse upon reaching the patient would operate the button 35 in such a way as to turn off the two lamps, the one the nurses' pilot lamp, the other the patient's door or bed lamp, and thereby discontinue the measurement of the time, so that the recorder would indicate 40 the length of time which elapsed between pushing the patient's button and the arrival of the nurse at the patient's bedside.

While this use of the apparatus is one for 45 which it was especially designed, it is adapted for other uses, and the invention consists in the elapsed time recorder hereinafter described and particularly defined in the claims.

In the accompanying drawings illustrating 50 the preferred form of the invention, Fig. 1 is a diagrammatic illustration of the circuits and various pieces of apparatus

comprising the complete system; Fig. 2 is a front view of the recording instrument; Fig. 3 is a side elevation of the same; Figs. 4 and 5 illustrate details of construction of the connector bar; Fig. 6 is a front elevation of the punches and their operating devices; Fig. 7 is a side elevation of the same, showing in addition the platen roll; Fig. 8 is a detail showing the spring 60 which restores the punch to normal position; Fig. 9 is a detail showing the paper feed drive gearing; and Fig. 10 is a section of the paper.

The illustrated embodiment of the invention is described as follows:

Referring first to Fig. 1, the apparatus consists of a recording instrument, of which two elements, viz., the solenoid 10 and one of the punch magnets and connections 11, 55 are shown separately for convenience of illustration, a relay 12, a master cock 13, and push buttons 14. The line wires 15, 16, supplying current to the apparatus, enter at the left of the diagram. The line 15 has three 60 connections, 17 running to the master clock, 18 to the solenoid, and a multiplicity of connections 19 running to the patient's push buttons 14. The solenoid 10 which actuates the recorder to advance the record strip 75 through the recorder is energized by a connection made by the master clock at intervals of one minute, the connection 20 of the master clock with the relay 12 operating 80 to energize the relay, which throws the armature 21 over into position to engage the contact 22 so that the current of the line 15 passes through the connection 18, the solenoid 10, the connection 23, the contact 22, 85 the armature 21, and thence to the line 16. At regular intervals the solenoid is energized 90 in this manner by the operation of the relay by the closing of the connection by the clock. The station taps 19 run each to a patient's 95 push button 14. Each push button is thus provided with current from the line 15. When the push button is depressed, it closes three connections, thereby conveying current through the connection 24 to the nurses' 100 buzzer 25, which is connected by the connection 26 with the contact 27, which engages the armature 21 when the relay 12 is de-

énergized, that is to say, when it is in its normal position unacted upon by the clock. The patient's push button is so arranged that when the button is first pushed and pressure is held on it by the patient, the contact of the connection 24 is made and continued so long as such pressure is exerted upon the push button (see Heeney Patent No. 1,170,063). When the patient releases the pressure upon the push button, this connection to the buzzer 25 ceases, and the buzzer stops. The other connections made by the patient's push button are through the connection 28 to the door or bed lamp 29, which is connected on the other side with the connection 26, so that upon closing the circuits, the patient's door lamp is illuminated. The third connection made by pressure exerted upon the patient's push button is through the connection 30, which conveys current to the nurses' pilot lamp 31. Pressure on the push button closes all three of the circuits to the buzzer, door lamp and the nurses' pilot lamp all at the same time, but while release of pressure on the push button opens the connection with the buzzer, it does not open the connections to the door lamp and the nurses' pilot lamp, as a result of which, even after the patient has removed pressure from the button, these lamps continue lit as an indication to the nurse that a call has been put in. Thus, it might happen that the nurse was engaged upon some other patient at the time the patient at 14 pushed his button. Then the nurse, upon returning to her desk, or upon entering the hall, would notice the desk pilot lamp or the door lamp, and could proceed immediately to the patient who rang from 14. When the nurse reached the bedside of the patient at 14, she would open the push button, thereby opening the circuits to the door lamp and nurses' pilot lamp. A fourth connection or circuit is closed by the patient upon pressing his push button. This is through the connection 28 to the door lamp and the connection 32 to the punch magnet 11, to which it is connected at 33. The other connection from the punch magnet 11, at 34, leads through the connection 35 to the connection 26. Thus, when the patient's button is pushed, the punch magnet 11 is energized, and it remains energized until the nurse reaches the patient's bedside and operates the push button to open the circuits again. The punch magnet operates a punch connected therewith in the recording instrument to punch a hole in the record strip passing through the instrument. The punch point 36, when operated by the punch magnet 11, punches its hole in the record strip and retreats from engagement with the paper of the record strip, but does not return to its original position, because the punch magnet remains energized. Now, the relation of the record strip feed to the punch magnet and

clock is as follows: Assuming the patients' push buttons to have remained unoperated, on each minute the clock energizes the solenoid circuit, which operates by means presently to be described to feed the record strip forward a distance corresponding to a minute. This feeding forward of the record strip continues uninterruptedly at all times. When no patient's push button has been operated, the record strip remains unmarked, but when a patient's push button is operated, four things immediately and simultaneously happen. First, the nurse's buzzer rings, her pilot lamp is illuminated, the patient's door lamp is illuminated, and the punch magnet is energized, thereby causing the punch to prick a hole in the record strip. This indicates the time when the patient pushed the button. Upon the patient's taking his finger off the push button, the buzzer ceases ringing, but the two lamps remain illuminated, and the punch magnet continues energized. Upon the next energization of the solenoid circuit by the closing thereof by the clock, the relay 12 opens the punch circuit (and incidentally the lamp circuits as well), the punch drops back to its inoperative position. Thereupon the relay is de-energized, and its armature moves back to the position illustrated in Fig. 1, thereby reclosing the patients' circuits, re-energizing the punch, causing it again to punch a hole in the paper, and again to illuminate the two lamps, and so on, at intervals of one minute, the punch is operated to prick holes in the paper after each forward feeding movement, thereby producing a record showing how many minutes elapsed from the time the patient pushed the button until the nurse operated the button to open the patient's circuit, and thus recording the length of time which elapsed from the giving of the signal by the patient until the nurse reached the bedside. This would be of great importance to the nurses because it would prove their alertness and attention, and incidentally the record strip would also show how many patients' push buttons were being operated per hour, and whether or not sufficient nursing attendance was supplied.

Fig. 10 shows an operation of the record strip. The longitudinal spaces marked with the numerals 1 to 24 identify the patients' push buttons, or stations, or rooms. Thus a series of dots or pricks marks in the paper at 40 indicate that the patient at station 8 had pushed his button. The paper is divided transversely by the hour and quarter hour lines, reading up from the bottom, marked 1:45, 2:00, 2:15, 2:30, 2:45, 3:00, 3:15. Thus the prick marks 40 would indicate that at approximately 2:31 P. M. the patient at station 8 operated his push button. There appearing five pricks in the paper before the patient's button was operated by the nurse

to open the patient's circuit, it is shown that five minutes, or thereabouts, elapsed before response was made to the call. The paper pricks 41 show that at about 2:51 P. M. the patient at station 14 rang in a call which was answered in about three minutes. So also, the paper pricks 42 indicate that the patient at station 19 rang in a call at 2:55, which was not answered until 3:17, so far as from 10 the record appears. Now, it might have been that the nurse, upon reaching the bed-side of the patient at station 19, found the emergency so pressing that the work of relieving the patient was attended to before 15 the opening of the circuit was attended to.

Passing now to the recording instrument, the record strip is wound in a roll 50, which is supported on a roll carrier 51, the end of which is received in bearings 52 in the frame 20 pieces 53. A weight roll 54 presses on the paper and offers a slight tension to the drawing of the paper from the roll. The record strip 60 drawn from the paper roll 50, passes around the bar 61, and thence over the surface 25 of the platen roll 63, which is a steel roll covered with felt. From this platen roll the record strip 60 passes on to the feed roll 64, over which it passes between the roll proper and a pressure roll 65. The record strip 60 is provided with holes 66 in its margin which receive the feed teeth 67 of the feed roll 64. From the feed roll 64 the record strip 60 drops down from the machine. The feed roll 64 has attached to 30 it a gear 68, which meshes with the gear 69, which, in turn, is driven by the pinion 70. The connection between the gears 68 and the feed roll 64 is by means of the friction washer 71, the washer being attached 35 to the feed roll and pressing with elastic pressure on the gear 68 by which they are held together in the manner of a friction clutch. The shaft of the feed roll is provided with a knurled hand wheel 72, so that 40 the feed roll may be turned by hand without movement of the driving train by which the roll is normally actuated. The pinion 70 is connected with the ratchet wheel 73, which is held from backward rotation by the spring 45 pressed pawl 74 and is racked forward by means of the solenoid lever 75, carrying a spring pawl 76, which, upon each actuation of the solenoid, operates to advance the ratchet wheel the distance of one tooth. The 50 solenoid lever 75 is connected by means of the link 77 consisting of a yielding coil spring with the core 78 of the solenoid 10. When the solenoid is energized the core is drawn up and the record strip is fed forward 55 a distance which corresponds to one minute of time.

The machine is provided with 24 punch magnets 11, of which 12 are like that shown in Fig. 1, and 12 have short punch carrying levers, as shown in Figs. 6 and 7. These

punch magnets carry on their punch levers a series of 24 punches arranged, as shown in Fig. 6, in a row, each punch pricking the paper at a place designating a station, so that each punch magnet represents a station. 70 A description of one of the punch magnets will suffice for all.

Referring to Fig. 7, the coil 80 is provided with a core 81 and a back piece 82, by which it is attached to the frame of the instrument. A post 83 carries the armature 84 pivoted at 85 on the post 83. The pole of the core 81 is cut away short of its end so as to localize the magnetic field at 86 near the end of the pole piece. The armature carries an angle piece 87, which projects along the side of the post 83 and is pressed upon by a spring 88 secured to the post 83, which normally tends to move the armature into the position shown in Fig. 7. The armature supports a punch lever 90, pivoted at 91 thereon. A screw 92 passes through a hole in the end of the punch lever 90 and screws into a threaded hole in the armature 84. A spring 93 is provided between the end of the punch lever 90 and the armature, and normally tends to hold the punch lever in position with relation to the armature, as shown in Fig. 7. When the coil 80 is energized, the pole of the core 81 attracts the armature 84, and thus the punch lever 90 is swung to cause the punch 94 to prick a hole in the paper by striking the paper where it is supported by the platen roll a light blow. The pivoting of the punch lever permits the punch to swing beyond the position which it would normally occupy under the attraction of the magnet on the armature. The spring 93 serves to 95 yieldingly hold the armature 84 and the end of the punch lever 90 in predetermined relation to one another and affords easy and accurate adjustment of the perforating pin 94 in relation to the roll 63. By screwing the screw 92 in or out, the desired adjustment of the 100 perforating pin may be secured. Remembering, now, that when the magnet is energized, it remains energized, it will be seen that the punch moves far enough to penetrate the 105 paper, and then springs back a little so that the punch is not in continuous contact with the paper. The record paper is moved ahead once each minute, and during the time that the paper is being moved, namely, during the extremely short interval of time 110 in each minute, the punches are prevented from penetrating the paper. The punch magnets are, however, in readiness to operate at all other times whenever a button is pressed. The only condition under which a call would not be recorded is when the call was made and reset within the very short interval of time that the paper is being moved. The series of punch magnets nearer 115 the platen roll are provided with short 120 levers, as shown in Figs. 6 and 7. These

punch levers 95, while the two outside series of punch magnets carry long levers 90. The platen roll is covered with a layer of felt to permit the punch to penetrate it slightly when it is operated.

A connector plate 100 of insulating material is supported across the top of the frame of the machine as shown, and carries twenty-four connectors 101, which may be 10 called the station connectors. This plate also carries a connector 102, which may be called the relay connector, and two connectors 103, which may be called the solenoid connectors. The outside wires 104 running to the connectors 101 come from the various stations or patients' push buttons, and the inside wires 105 from these connectors respectively pass each to one of the punch magnets. The relay connector 102 on the outside is connected by 20 a wire 106 with the contact 27 of the relay, and the wires 107 running down through the hole in the connector supporting plate from the connector 102 run to the other terminals of the several punch magnets. The wires 107 25 are common to all the punch magnets, so that there are only two wires 107 coming from the connector plate at the top which are connected to one of the terminals on each of the punch magnets.

30 A wire 108 from the outside running to the connector 103 is connected with the contact 22 of the relay. A wire 109 on the front connector 103, as shown in Fig. 4, is connected with the line wire 15. Then the two wires 110 from the two connectors 103 run down to the solenoid.

Fig. 5 shows a cross-section of the connector supporting plate 100 taken on the line 5—5, Fig. 4.

40 The particular form of punch magnet used herein forms the subject of an application filed by the present inventor January 5, 1922, and operates very silently because the blow struck by the punch is received against 45 the felt covered platen roll, and the armature does not strike any part when the magnet is energized. The solenoid lever 75 is provided with stops 120, shown in Fig. 3, each being provided with pieces of felt against which 50 the lever will strike at the extremes of its movements. Thus, when the solenoid is energized and the lever is raised, it strikes against the upper stop and without any audible blow, and when the solenoid is de- 55 energized, the core drops and the solenoid lever strikes against the lower stop, similarly without sound.

The record strip upon closure of the feeding circuit under the influence of the master clock by the armature of the relay 12 operates to perform the desired feeding of the paper without tearing it. This result is secured because the solenoid 10 is inherently somewhat slow in action, due to some extent 60 to the presence of an air cushion above the

70 plunger 78, or its dash pot effect, and furthermore the link 77 between the plunger 78 and solenoid lever 75 is purposely made yielding so that upon upward movement of the plunger 78 when the solenoid is energized, the combined effect of the cushion above the plunger and the yielding spring link 77 operates to eliminate or to smooth out a considerable portion of the suddenness 75 of the motion imparted to the solenoid lever 75. Furthermore the gear train by which the movements of the lever 75 are transmitted to the feed roll 63 still further reduces this suddenness of motion so that as a result when the solenoid is suddenly energized by closure of the relay 12, its operation 80 is caused to turn the feed roll 63 gradually, thus eliminating all tendency toward tearing the paper. This feature of the invention is 85 conducive to the successful operation of the system.

The instrument is prepared for use by providing it with a roll of record strip which is put in place as shown in Fig. 3, the 90 end of the strip being brought forward over the rod 61, thence passed behind the platen roll 63, thence forward over the feed roll 64, and down between the feed roll and the presser roll 65. The knurled wheel 72 may then be turned by hand to bring the proper time line on the record strip opposite the punch roll, the friction clutch connection between the feed roll and its drive mechanism slipping as the adjustment is made. The 95 printed surface of the paper is toward the front of the machine, so that the portion discharged from the instrument may be examined without removal, like a piece of ticker tape.

Having thus described the invention, what 100 is claimed is:

1. In a time recorder system, the combination of a recording instrument provided with a record strip and means for intermittently feeding the record strip including a strip engaging device, a solenoid and a yielding connection between the solenoid and strip engaging device.

2. In a time recorder system, the combination of a recording instrument provided with a record strip and means for intermittently feeding the record strip including a feed roll, a solenoid having a plunger, a gear train connected with the feed roll and yielding connections between the solenoid plunger and gear train.

3. In a time recorder system, the combination of a recording instrument provided with a record strip and means for intermittently feeding the record strip including a feed roll, a solenoid having a plunger, a gear train connected with the feed roll, and means for intermittently actuating the gear train and feed roll upon movement of the plunger when the solenoid is energized.

including a ratchet, a pawl and a spring connecting the pawl with the solenoid plunger.

4. In a time recorder system, the combination of a recording instrument, and means for intermittently feeding the record strip including a dash pot controlling device for preventing sudden operation of the feeding device.

10 5. An elapsed time recorder having, in combination, a clock, a recording instrument comprising a magnet, an armature, a marker yieldingly pivoted on the armature and a tape feed roll, a station push button, a circuit including the magnet and the push button for normally maintaining the magnet energized while the push button is depressed, feeding means for the tape roll, connections between the clock and the feeding means for 15 operating the latter at time intervals, and means for de-energizing and energizing the

magnet to actuate the marker when the feeding means is actuated.

6. An elapsed time recorder having, in combination, a clock, a recording instrument 25 comprising a magnet, an armature, a marker yieldingly pivoted on the armature and a tape feed roll, a relay having two contacts, a stationary push button, a circuit including the push button, the magnet and one relay 30 contact, connections between the clock and the relay for operating the latter at time intervals, feeding means for the tape roll, and a circuit including the second contact of the relay and the roll feeding means and adapted to be closed when the relay is energized, whereby the magnet will be de-energized and again energized to actuate the marker at time intervals corresponding to the operation of the relay. 35

CYRUS T. SCHIRMER.
